[57] CLAIM

The ornamental design for a combined dispensing sealing closure and cap for bottles, as shown and described.

DESCRIPTION

FIG. 1 is a perspective view of a combined dispensing sealing closure and cap for bottles showing my new design;

FIG. 2 is a left side elevational view thereof;

FIG. 3 is a right side elevational view thereof;

FIG. 4 is a front side elevational view thereof;

FIG. 5 is a rear elevational view thereof;

FIG. 6 is a top plan view thereof;

FIG. 7 is a bottom plan view thereof; and,

FIG. 8 is a perspective view thereof, similar to FIG. 1, with a cap mounted onto the cork.

FIG. 1

FIG. 2

FIG. 3

FIG. 4

FIG. 5

FIG. 6

FIG. 7

FIG. 8
